UNITED STATES PATENT OFFICE.

WILLIAM HENRY MORGAN, OF SENECA, ILLINOIS.

PIPE-THREADING DEVICE.

SPECIFICATION forming part of Letters Patent No. 774,597, dated November 8, 1904.

Application filed May 11, 1904. Serial No. 207,464. (No model.)

To all whom it may concern:

Be it known that I, WILLIAM HENRY MORGAN, a citizen of the United States, residing at Seneca, in the county of Lasalle and State of Illinois, have invented a new and useful Pipe- Threading Device, of which the following is a specification.

This invention relates to metal-working tools, and has for its object to provide an improved device of this character for facilitating the cutting of threads upon pipes, and especially upon very short lengths of pipes.

It is furthermore designed to accommodate the device to hand-operated thread-cutting stocks of different sizes, to rigidly support the work during the operation of the device, and to maintain the thread-cutting stock in proper relation with respect to the work.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a sectional elevation of a thread-cutting device embodying the features of the present invention. Fig. 2 is a detail sectional perspective view of the work-holding socket. Fig. 3 is a detail sectional elevation illustrating the device employed in the production of a stud-bolt.

Like characters of reference designate corresponding parts in each and every figure of the drawings.

For the support of the present device there has been shown an ordinary work-bench 1, having a pipe-vise 2 thereon and including the usual clamping-screw 3. Supported by the pipe-vise 2 is a guide rod or bar 4, having one end portion circular in form and the opposite end non-circular, with either end capable of engagement with the vise, according to the character of work to be performed by the

device. Upon the guide rod or bar is a cylindrical socket member 5, one end of which is open and increased in thickness, so as to receive the screw-threads of the threaded openings 6, wherein are fitted radial set-screws 7. The opposite end of the socket is closed by an integral head 8, through the center of which is provided a non-circular opening 9 to receive the non-circular portion of the guide-rod and prevent rotation of the socket thereon, while at the same time permitting of a slideable movement of the socket to apply and remove the same and to adjust the socket to any position upon the guide-rod. It will of course be understood that the guide-rod 4 is of a length to project at opposite ends of the socket 5 in order that one end may be connected with the pipe-vise and the other end may constitute a support for any ordinary or preferred form of thread-cutting device. After the guide-bar and the work-receiving socket have been assembled and supported in the vise the pipe to be threaded, which has been illustrated at 10, is slipped over the outer end of the guide-rod and fitted into the open outer end of the work-receiving socket, the set-screws 7 being set against the pipe to hold the same against endwise and rotary movement. Any ordinary hand-operated thread-cutting tool 11 is then fitted upon the outer end portion of the guide-rod 4, with its stationary tubular supporting member 12 fixed against rotation by means of a set-screw 13, carried thereby and engaging the guide-rod. The body of the tool carries an internally-screw-threaded sleeve 14, which embraces the externally-screw-threaded portion of the stationary member 12, so that when the bits or dies of the tool have been set to fit the pipe 10 and the member 12 clamped upon the guide-rod 4 threads may be cut upon the pipe by rotating the tool or stock 11 in the usual manner. After the work has been completed the thread-cutting stock may be readily removed by releasing the set-screw 13, and the pipe may be released by loosening the set-screws 7.

From the foregoing description it is ap-

parent that the guide-bar and work-receiving socket of the present invention enables the employment of thread-cutting stocks or tools of different sizes, and if it is desired to sever 5 a pipe a pipe-cutting tool may be substituted for the screw-threading tool without requiring any change whatsoever in the other parts of the device.

Another advantage of the present device re-
10 sides in the fact that the work projects out-
wardly from the work-holder 5 and the cut-
ting-tool is supported upon the guide-rod 4
entirely in front of the work and the work-
holder and approaches these elements from
15 the front thereof, wherefore very short
lengths of pipe may be conveniently threaded.

The device may also be used for removing
10 short nipples from couplings, valves, unions,
and the like by inserting the nipples within
20 the work-holder, setting the screws 7 against
the nipple, and then rotating the coupling,
valve, or union by means of a pipe-wrench,
whereby the nipple will be unscrewed and re-
main in the work-holder, from which it may
25 be removed after releasing the set-screws 7
without any injury whatsoever to the threads
of the nipple. In using the device for this pur-
pose the supporting rod or bar 4 is reversed,
so as to have the squared end thereof pro-
30 jected in front of the bench-vise sufficiently
only for the support of the work-holder 5, for
the reason that should the bar project a con-
siderable distance in front of the work-holder
it would prevent valves and the like from be-
35 ing engaged with the work-holder.

By removing the device from the vise-
bench and reversing the position of the sup-
porting-bar 4, so as to have the same pro-
jected at the rear only of the work-holder,
40 the latter may be fitted to a nut by having the
set-screws 7 set against opposite edges of the
nut, and then by applying a wrench to the
bar the nut may be removed or applied in a
very convenient manner, where it might not
45 be possible to have access to the nut by means
of an ordinary wrench.

As illustrated in Fig. 3 of the drawings, the
present device may be employed in the for-
mation of stud-bolts or bolts which are thread-
50 ed at opposite ends. In this use of the de-
vice the supporting-bar 4 is projected entirely
at the rear of the work-holder and held in a
bench-vise, as hereinbefore described, while
the intermediate unthreaded portion of a stud-
55 bolt 15 is gripped between the set-screws 7,
wherefore any common or preferred form of
die-stock or screw-threading tool 16 may be
fitted to the projected end of the work to
screw-thread the same, after which the posi-
60 tion of the work may be reversed, so as to
give access to the opposite end thereof for
threading the same. It will here be noted
that the set-screws 7 engage the intermediate

unthreaded portion of the bolt, and therefore
no damage results to the screw-threads when
65 the position of the work has been reversed.

The purpose of having the combined guid-
ing and supporting bar cylindrical for a
greater portion of its length and non-circular
at one end is to prevent rotation of the work-
holder when fitted to the non-circular portion,
70 while the cylindrical portion is designed to
fit within the circular openings of die-stocks
or thread-cutting tools, so as not to interfere
with the convenient rotation thereof.

Having thus described the construction and
operation of my invention, what I claim as
new, and desire to secure by Letters Patent,
is—

1. A device of the class described including
a guide-bar and a work-holder carried there-
by with the guide-bar projected at opposite
ends of the work-holder, one end of the bar
being formed for connection with a support,
and the opposite end being formed for the
85 support of a tool in coöperative relation with
the work-holder.

2. A device of the class described including
a bar and a tubular work-holder disposed con-
centrically thereon and provided with means
for clamping the work to the holder, the op-
posite ends of the bar being projected beyond
90 the work-holder, one projected end portion
of the bar being formed for connection with
a support, and the opposite projected end por-
tion being formed for the support of a tool in
coöperative relation with the work-holder.

3. A device of the class described including
a work-holder having a non-circular opening,
and a bar having one end portion cylindrical
100 in shape and its opposite end portion non-cir-
cular to fit the opening of the work-holder
and capable of being reversed to project the
bar at either end of said holder.

4. A device of the class described including
a bar having a non-circular portion, and a
hollow work-holder having a non-circular
opening receiving the non-circular portion of
the guide-bar and provided with means for
105 clamping the work within the holder, the
guide-bar being projected at opposite ends of
the holder for connection at one end with a
support and for supporting a cutting-tool
upon the opposite end of the bar.

5. A device of the class described including
a bar having a non-circular portion, and a
work-holding socket slidable upon the bar
with one end provided with a non-circular
opening receiving the non-circular portion of
110 the bar and also provided with set-screws
piercing the socket to clamp the work there-
in, the guide-bar being projected at opposite
ends of the work-holder for connection at one
end with a support and for supporting the
115 cutting-tool at its opposite end.

6. A device of the class described including

a work-holder having set-screws piercing the same and provided with a non-circular opening in its otherwise closed rear end, and a supporting-bar having a non-circular portion 5 to fit the non-circular opening of the work-holder and capable of being reversed to project at either end of the work-holder.

In testimony that I claim the foregoing as my own I have hereto affixed my signature in the presence of two witnesses.

WILLIAM HENRY MORGAN.
